UNITED STATES PATENT OFFICE.

WALTER WILBUR, OF LYNDEN, WASHINGTON.

CLOTHES-WASHING APPARATUS.

1,264,356.

Specification of Letters Patent. Patented Apr. 30, 1918.

Application filed March 30, 1916. Serial No. 87,808.

To all whom it may concern:

Be it known that I, WALTER WILBUR, a citizen of the United States, residing at Lynden, in the county of Whatcom and 5 State of Washington, have invented certain new and useful Improvements in a Clothes-Washing Apparatus, of which the following is a specification.

This invention relates to a clothes washing apparatus and has for its object to 10 provide a portable device of this character which may readily be transported from place to place and placed within a tub containing clothes to be washed and being held 15 manually in position, is adapted to be operated by power or by hand.

Another object of the invention is to provide in a portable washing apparatus having a vertically movable piston in a cylinder 20 and operated by power, means for varying the operative position of the piston within the cylinder whereby the movement of water during the washing process is varied and varying results obtained.

25 Further objects of the invention not hereinabove mentioned will be brought out fully in the following description and illustrated in the accompanying drawings, in which:—

Figure 1 is a side elevation of the complete apparatus.

Fig. 2 is a top plan view of the same.

Fig. 3 is a horizontal sectional view on the line 3—3 of Fig. 1.

Fig. 4 is a like view on the line 4—4 of 35 the same figure.

Fig. 5 is a bottom plan view of the apparatus, and

Fig. 6 is a vertical central sectional view through the cylinder and piston.

40 Fig. 7 is a detail view illustrating a means for operating the machine manually.

Fig. 8 is a sectional view through a portion of the plunger showing a relief valve for use therewith.

45 Referring to the drawings in which similar reference characters designate corresponding parts throughout the several views, 10 indicates a cylinder which in the normal position of the apparatus stands vertically,

50 said cylinder being open at the bottom and closed at the top by a removable cover 11 through which are formed air openings 12. A short distance above the bottom of the cylinder is secured an outwardly flaring or 55 conical flange 13 forming a skirt that extends downwardly into the plane of the bot-

tom of a cylinder. An annular closure 14 extends between the bottom of the cylinder 10 and the bottom of the skirt 13 forming thereby a water chamber 15 that communicates just below the attachment of the skirt to the cylinder with the interior of the cylinder by means of a circular row of openings 16. A plurality of perforations 17 are formed in the annular closure 14 to permit 60 the entrance of water into the chamber 15 and from there into the cylinder through the holes 16.

For the purpose of transporting the cylinder from place to place and manipulating the same when in use, a straight vertical bar 18 is rigidly connected to the cylinder by stepping its lower ends in a socket 19 and securing it by an encircling strap 20 near the top of the cylinder. Rigidity 70 of the bar is insured by means of brace rods 21 connected to ears on a ring 22 surrounding the bar 18 above the cylinder and extending downwardly and angularly to ears 23 on the upper edge of the cylinder 10. 80

Within the cylinder 10 is a piston 24 the periphery of which is free of the walls of the cylinder to reduce friction, but to prevent the passage of water around the piston the latter is grooved and a soft packing 85 25 that bears against the cylinder is inserted in said groove. The bottom of the piston 24 is covered by a disk of rubber 26 or other equivalent material of the full diameter of the piston and roughened or 90 corrugated in any suitable manner on its exposed face. As shown in Fig. 5, one form of roughening consists in making a plurality of radial grooves 27 in the lower face of the disk, thus producing channels for the 95 passage of water between raised triangular portions 28 that bear upon and press against the clothes being washed.

A piston rod 29 extends from the piston 24 through the cover 11 in an upward direction parallel to the bar 18 for a suitable distance where it is pivoted to a guiding head 30 comprising a pair of plates 31 between which the end of the piston rod extends and through which the pivot pin 32 100 passes. The head 30 is arranged to slide freely on a vertical guide plate 33 mounted on the outer ends of spacing blocks 34 projecting from the bar 18 and bolted thereto as shown. Above the spacing blocks 34 and 110 projecting in the opposite direction is another spacing block 35 bolted to the bar 18.

and depending from said block is a bearing bracket 36 to which is pivoted a substantially horizontal lever 37 formed as here shown of two bars 38 that pass on opposite sides of the bar 18 for a distance greater than the diameter of the cylinder 10 and have bolted to their outer ends a handle 39 by means of which the lever 37 is vibrated in a vertical direction.

10 Securely fastened on the handle 37 and extending below the same is an electric motor 40 of any approved type on the shaft 41 of which is keyed a disk 42 from one side of which projects a crank pin 43 that is journaled on one end of a connecting rod 44. The opposite end of said rod passes between the plates 31 of the pitman head 30 and is pivoted thereto.

Current from any source of power is conducted by wires 45, 46 to the motor which being driven by said current causes a rapid rotation of the crank disk 42 and through the connection of rod 44 with the head 30, and piston rod 29, the piston is given a very rapid reciprocation in the cylinder 10. The stroke of the piston 24 may be varied by inserting the crank pin 43 in one or the other of the holes 47 in the crank disk 42, thereby changing the length of crank movement 30 and consequently the movement of the piston.

In Fig. 7 is illustrated a modified form of invention that enables the apparatus to be used where it is impossible to obtain electric power. In this case, a link 48 connects the handle 37 directly to the head 30 so that rapid oscillation of the handle 37 reciprocates the piston 24 in the cylinder 10. By raising or lowering the handle the position of the piston within the cylinder is changed 40 as is evident.

While I have shown the best form of the device known to me at the present time, it is to be understood that various changes and modifications in the construction and arrangement of parts may be made without departing from the spirit of the invention and that all such changes as come within the scope of the claims are to be considered as covered thereby.

50 What I claim as new is:—

1. In a portable clothes washing apparatus, the combination of a cylinder adapted to be placed within the wash tub, a piston reciprocable within said cylinder, a hand

bar extending upwardly from the cylinder, 55 means for reciprocating said piston, and a support for said reciprocating means movable with said means in the axial line of the cylinder for changing the stroke position of the piston within the cylinder during the 60 reciprocation thereof without varying the length of the piston stroke or stopping the operation of the apparatus.

2. In a portable clothes washing apparatus, the combination with a cylinder 65 adapted to be placed within a wash tube, a piston within said cylinder, a hand bar extending upwardly from said cylinder for manually supporting the same in the tub, means movably mounted on said bar for 70 imparting short reciprocations to said piston, and a hinged support carrying said reciprocating means for varying the position of the piston within the cylinder during its reciprocation.

75 3. In a portable clothes washing apparatus, the combination with a cylinder adapted to be placed within a wash tub, and a piston reciprocable within said cylinder, of a hand bar extending upwardly from said 80 cylinder for supporting the same within the tub, a motor connected directly to said piston for imparting short reciprocations thereto, and manual means pivoted to said bar for supporting said motor and adapted 85 to swing vertically for changing the position of the piston within the cylinder during its operations.

4. In a portable clothes washing apparatus, a cylinder adapted to be placed within 90 the wash tub and movable freely therein, a piston reciprocable within the cylinder, power means for imparting strokes of predetermined length to said piston, and manually operable means supporting said power 95 means and movable to and from the cylinder for changing the stroke position of the piston within the cylinder coincidentally and independently of reciprocations and without interrupting the continuity of the reciprocations.

In testimony whereof I affix my signature in presence of two witnesses.

WALTER WILBUR.
